UNITED STATES PATENT OFFICE.

HARRY W. BROADY, OF BAYSIDE, NEW YORK, ASSIGNOR TO WELIN MARINE EQUIPMENT COMPANY, A CORPORATION OF NEW YORK.

ENGAGING AND DISENGAGING GEAR FOR SHIPS' BOATS.

1,168,377.

Specification of Letters Patent.

Patented Jan. 18, 1916.

Application filed June 6, 1914. Serial No. 843,392.

To all whom it may concern:

Be it known that I, HARRY W. BROADY, a citizen of the United States, and a resident of Bayside, borough of Queens, county of 5 Queens, and State of New York, have invented certain new and useful Improvements in Engaging and Disengaging Gear for Ships' Boats, of which the following is a specification.

10 This invention relates to improvements in engaging and disengaging gear for ships' boats and particularly an improvement in the type of gear illustrated in Letters Patent to W. Mills, #512,045, of January 2d, 15 1894.

The object of the present invention is to produce a device in which the operating or hook-disengaging connections are so arranged as to multiply the power of the operator, so as to enable a comparatively short hook-disengaging lever to be employed and to enable the application of such multiplied power equally to hooks at opposite ends of the boat to cause a simultaneous release 20 thereof; and to permit the first pulley over which the operating connections pass from the hook to be positioned at a point adjacent to the bracket in which the hook is pivoted and also to permit the bearings of such pulley to be formed integrally with such bracket, whereby a more compact, stronger and more rigid construction may be made.

In the accompanying drawings in which similar reference characters designate corresponding parts throughout the several views, Figure 1 is a vertical longitudinal section of a metallic boat equipped with a gear made in accordance with my invention; Fig. 2 is a plan view of the metallic boat illustrated 30 in Fig. 1; Fig. 3 is an enlarged side elevation of the device shown in Figs. 1 and 2; Fig. 4 is a perspective view of a hood preferably employed by me which fits over the supports for the hook.

45 Referring now to these drawings, 1-1 are forked supports or ring guiding members, one of which is rigidly and firmly retained at each end of the boat and, as shown, is securely attached to the shell plating there- 50 of by brackets 2-2. Each of such forked supports or ring-guiding members has integrally formed therewith at its upper end a surface or top plate 4, which plate is provided with an opening 5 of sufficient size to 55 permit the entrance of the ring or eye of the

pulley or other boat-hoisting and lowering apparatus (not shown). The said forked support 1 is preferably made V-shaped at its upper end so as to guide the ring or eye of the pulley block into position when lowered into said opening 5 of the plate 4, and a tripping or engaging hook 7 is pivoted intermediate its ends and so positioned in relation to each of the forked supports below the V-shaped ring guiding portion that 60 it will readily engage or hook over said pulley ring or eye. Each tripping hook is provided with a stem 8 extending below the pivotal point and the lower end of said stem has a counterweight 9. Devices, or parts of 65 devices, substantially similar to those above described are included in said patent to Mills No. 512,045 and are common in the art, and my invention consists in combining 70 with such old devices the novel features and 75 arrangements which will now be described.

An eye 10 is positioned on each stem 8 intermediate the pivotal point and said weight so as to afford a comparatively short 80 releasing or disengaging lever between said point and the pivot of the hook.

Arranged along the inner side of the gunwale of the boat and suitably guided to permit ready sliding or longitudinal movement thereof are rods 11-11 and to one of the 85 ends of each of such rods is secured two chains 12-12 or other flexible connections, which chains are guided in opposite directions and pass over pulleys 13 mounted in bearings which are formed integral with 90 the top or the surface plate 4, and the opposite ends of such chains 12-12 are connected to the eyes 10 on the stems of the tripping hooks at opposite ends of the boat. It will be apparent that it is desirable to 95 position this pulley as close to the said plate as possible first, for reasons of economy of manufacture; second, to procure a compact and very rigid supporting structure, and third, to enable the placing of these engaging and disengaging devices close to the respective ends of the boat to facilitate nesting of two or more boats and also to facilitate installation of the device. It will also be understood that the entire weight of the 100 boat, which in some cases amounts to many thousand pounds, must be supported by these hooks and brackets and furthermore that, while it is a comparatively simple matter to install a device having this integrally 105 110

mounted pulley in its closely adjacent position, it is much more difficult to attach a separate pulley in a distant position on the under surface of the deck of the boat. To enable the positioning of this pulley adjacent to the hook, I have found it necessary to connect the chains intermediate the pivot and the counter-weight, which would permit only a relatively short leverage as aforesaid. Such a short leverage, however, would, with old arrangements, make it substantially impossible for one man to operate or disengage the hooks, and in order to enable the facile operation of the hooks by one man and the simultaneous releasing of the tripping hooks at opposite ends of the boat, I provide the contiguous ends of the jointed rods 11-11 with pulleys 13-13 which are secured to or mounted in the ends of such rods and are movable or travel therewith, and have an actuating chain or rope 14 which is fixed intermediate its ends as at 14^a, the opposite strands or portions of which are led in opposite directions and pass over the pulleys 13-13 at the ends of the rods and then double backwardly passing over pulleys 15-15, the ends of such strands being connected to a handle 16. By this arrangement I am enabled to multiply the power applied to the rods and make it possible to employ the short leverage hereinabove referred to.

A hood 20 having a top plate 20^a and two side-plates 20^b and 20^c respectively is fitted over the forked supports 1 so that the plate 20 rests upon the surface plate 4 of such forked supports, and said top plate 20^a is provided with an opening or aperture 21 which registers with the opening 5 of the plate 4. The side plates are rounded at their rear portion to conform with the configuration of the shell plating of the boat and are connected thereto by angle irons 22-23.

The operation of the device will be obvious from the above.

Having described my invention, I claim:

1. In engaging and disengaging gears for ships' boats, the combination with a pair of counter-weighted tripping hooks, means for

supporting one of such hooks at each end of the boat, connections with opposite hooks suitably guided within the boat and extending toward each other, each connection having a pulley journaled at its end, an independent flexible connection passing over each of said pulleys, said connections having one of their ends fixed to the boat and the opposite end terminating adjacent to each other, and a common pulling-handle attached to said opposite ends as and for the purpose specified. 60

2. In engaging and disengaging gear for ships' boats the combination with a pair of tripping hooks pivoted intermediate its ends and provided with a counterweight, two connections having one of their ends engaging the hooks intermediate their pivotal points and the counterweights, said connections being suitably guided within the boat, extending toward each other, and having pulleys journaled at their ends, a flexible connection fixed intermediate its ends at a point between the ends of the connections having the pulleys to form independently-movable and oppositely disposed strands, one strand of such flexible connection passing over each pulley, a handle connecting the ends of the strands whereby the manipulation of said handle will cause the connections and pulleys to move toward each other to simultaneously release the tripping hooks at the opposite ends of the boat. 75

3. In engaging and disengaging gear for ships' boats a tripping hook, a pulley-ring guiding bracket and means for supporting the same, said bracket provided with a surface plate having a ring insertion opening, a hood fitting over said bracket having a ring insertion opening registering therewith and having independent connections with the boat at opposite sides of said bracket. 90

In witness whereof, I have signed my name to the foregoing specification in the presence of two subscribing witnesses.

HARRY W. BROADY.
